EDWIN LESLIE BISHOP, OF BIRMINGHAM, ENGLAND

METHOD AND MEANS FOR CREEASING CARDBOARD AND LIKE MATERIAL

Application filed March 9, 1927, Serial No. 173,932, and in Great Britain March 23, 1926.

My invention has relation to apparatus for and/or a mode of treating or creasing straw-board, cardboard and like material (hereinafter referred to as "the board") so that it can 5 easily be bent or folded for use in the manufacture of boxes and the like. In order to render "the board" foldable, it is the usual practice to provide a crease therein of **U** section, as for instance, by a pressing machine, this **U** section crease permitting of the folding of "the board" without any splitting. The present invention has for its object to provide for the **U** section treatment or creasing of "the board" more expeditiously and 15 generally more efficiently than heretofore was the case.

According to the present invention, apparatus for treating or creasing "the board" comprises in combination two wheels or like 20 elements adapted to rotate at a uniform speed, the faces whereof are disposed in angular relationship so that the rims of the wheels or the like at one point are spaced slightly apart and adapted to diverge from one another to 25 constitute a wedge-shaped space, a deflector disposed immediately above or associated with such space, and means such as rollers co-operating with one of the first mentioned wheels or like elements, for flexing "the board".

Further, according to my invention, the apparatus comprises in combination two side by side wheels, or like elements, adapted to rotate at a uniform speed upon axes intersecting 35 in oblique or obtuse relationship, a plurality of rollers or equivalent means for compelling "the board" to follow the peripheral contour of one wheel or like element, and a deflector immediately above the wedge-shaped cavity occurring between the wheel rims and faces 40 adapted to urge "the board" into such cavity to effect the creasing operation.

In the foregoing apparatus means may be 45 provided for adjusting the effective operative space at the point of adjacency between the wheels or like elements, and, further, means may be also incorporated in combination with the foregoing, or separately, for adjusting the setting of the wedge-shaped cavity in relation to the deflector.

In operation "the board" is fed on to the rotating wheels, discs or like elements beneath the deflector, and during its movement through the apparatus it is bent by the rollers or equivalent device to an arcuate formation to follow the contour of at least one of the wheels or like elements, and is also flexed transversely to an obtuse or equivalent angular formation, by means of the deflector which urges "the board" between the wheels and 55 forms the **U** shaped crease, as hereinafter more particularly described and illustrated.

My invention further consists in an improved mode of creasing or treating "the board" so that it can be easily bent or folded, 60 consisting in bending "the board" to an arcuate formation upon a rotating annular body, further bending said "board" transversely to an obtuse angle formation, and directing "the board" at or about the junction of said angle 65 between two converging bodies such as rotating wheels to form a laterally compressed **U** shaped crease in "the board".

In order that this invention may be clearly understood and readily carried into practice, 70 reference may be had to the appended explanatory sheet of drawings, upon which:—

Figure 1 illustrates apparatus for treating or creasing cardboard according to the present invention, in part sectional elevation.

Figure 2 is a sectional end elevation of the apparatus shown in Figure 1.

Figures 3, 4 and 5 are diagrammatical views, hereinafter referred to, illustrating the actual operation of creasing.

In a convenient embodiment of the present invention I employ a main frame or structure *a* wherein a horizontal shaft *b* is rotatably mounted, and adapted to be driven at will, as for instance, from pulley mechanism *b*¹. *c*¹ is a sleeve keyed to the shaft *b* but adapted to slide thereon, said sleeve carrying the wheel, or like element, *c* which is provided with a rim *c*² of **L** section. This wheel, or like element, *c*, therefore, has a 90 cylindrical peripheral face and an inner abrupt face at right angles thereto. *d*¹ and *d*² are levers fulcrumed upon the sleeve *c*¹ and united by a pin *d*³, and the lever *d*¹ is provided with a boss *d*⁴ the axis of which 100

is disposed obliquely to the axis of the shaft *b* and intersects therewith. Rotatably mounted upon this boss *d*⁴ is the wheel, or like element, *d* complementary to the wheel, or like element, *c*, and this wheel *d* is provided with the particular rim *d*⁵ illustrated, which renders the wheel, or like element, of conical formation. It will be seen from the right hand half of the Figure 1 that the 5 wheels, or like elements, *d* and *c* are placed in close proximity at their upper part (see also particularly Figure 3), and, further, at this point the rims are facially aligned horizontally. The conical wheel *d* has an inner 10 abrupt face *d*⁶ adapted to lie parallel to the corresponding abrupt face *c*³ on the wheel *c* at the point of adjacency. The wheel, or like element, *c* is connected to the wheel, or like element, *d* by a flexible driving disc *c*⁴, such as is used in the universal joint of a 15 motor vehicle. Further, the two wheels, or like elements, are urged apart by means of a helical spring *c*⁵, a stop *c*⁶ being provided upon the sleeve and a thrust bearing *c*⁷.

20 The wheels, or like elements, *c* are preferably externally of serrated or roughened formation, and adapted to co-operate with these wheels, or like elements, are a plurality of spring pressed rollers *e* carried by a slide *e*¹ mounted upon an upper guide rail *a*¹ of the frame or structure *a*. This slide *e*¹ has a lug *e*² which is perforated and tapped to receive a horizontal screw-threaded shaft *f*. Provided upon the slide *e*¹ is a bracket *g* 25 which is longitudinally slidable for adjustment purposes in relation to the slide *e* by means of a screw pin *g*¹. This bracket *g* is extended downwardly at *g*² and carries a vertical adjustable holder *g*³ for the deflector *h*, which is spaced immediately above and/or partially within (according to adjustment) the wedge-shaped cavity occurring 30 between the wheels, or like elements, and may terminate (see Figure 2) slightly previous to the point of adjacency of the said wheels, or like elements. Its lower face *h*¹ preferably extends horizontally, after which it is directed slightly upwardly at *h*² slightly preceding the point of adjacency of the 35 wheels, or like elements. *g*⁴ are plain apertures in the bracket *g* for the reception of the screw-threaded shaft *f*.

40 It will be appreciated from the Figure 1 that the mechanism hereinbefore described is duplicated and oppositely arranged whereby a portion of "board" may have two parallel creases simultaneously inserted therein, and the adjustment means for varying the space between these creases involves the following mechanism:—The shaft *i* whereon it will be seen right and left hand threads are cut, and which is journaled in the frame *a*, wheel-carrying arms *j* having bosses *j*¹ engaging the respective screw threads on the shaft *i*, gear wheels *k*, one of which may have

a handle *k*¹, and which gear together shafts *i* and *f*. The wheel-carrying arm *j* has a hollow bearing boss *j*² (Figure 1) interposed between the levers *d*¹ and *d*² and other mechanism hereinafter described. Rotation of the shaft *i* as for instance by the operation of the handle *k*¹ causes the lateral displacement of the arms *j* and consequent adjustment of one wheel mechanism *c d* in relation to the other oppositely arranged and complementary wheel mechanism *c d*. Synchronized with this movement is the movement of the rollers *e* and deflector *h* consequent upon the rotation of the top shaft *f* whereby these members always assume a correct relationship to their respective wheels *c* and *d*. *l* and *m* are longitudinal stationary shafts parallel to the shafts *f* and *i*, and upon these shafts a bracket extension *j*³ of the wheel-carrying arm *j* is adapted to slide. This extension *j*³ carries bearings *j*⁴ and a manually rotatable shaft *n* having a screw connection *n*¹ with a boss *n*² on one extremity of a link *n*³, which is coupled to the pin *d*³ uniting the levers *d*¹ and *d*². Fulcrumed to the boss *n*² are dual wedge elements *o* having inclined faces *o*¹ adapted to co-operate with corresponding inclined faces provided upon the bearing *j*² of the wheel carrying arm *j*. *p* is a table whereon "the board" is placed, said table terminating (as shown particularly in Figure 2) immediately beneath the deflector *h*.

By rotation of the handle *n*⁴ the boss *n*² is displaced along the shaft *n*¹ and the levers *d*¹ *d*² thereby pivoted on the sleeve *c*¹ which is fixed so far as rotation is concerned. This pivotal movement of the levers *d*¹ *d*² rotates the obliquely set boss *d*⁴ and causes the point of adjacency of the wheels, or like elements, to be adjusted circumferentially of the wheels and in relation to the fixed deflector *h*.

In this manner, therefore, by the operation of the handle *n*⁴ the circumferential relation between the deflector *h* and the wedge-shaped cavity occurring between the wheels or like elements can be readily varied to suit particular requirements. Further, simultaneously with the operation of the handle *n*⁴, the wedge elements *o* are actuated, thereby adjusting the effective space between the wheels, or like elements, at their point of adjacency, as will be seen from the Figures 1 and 2. For instance, by the downward movement of the wedge elements *o* the spring *c*⁵ is permitted to thrust the wheels *c* and *d* further apart.

With the present machine, therefore, in order to adapt same to different thicknesses of board, it is only necessary to operate the handle *n*⁴, thus effecting the dual function of adjusting the circumferential point of adjacency of the complementary wheels, or like elements, in relation to the deflector, and also adjusting the spacing of the said wheels or like elements at their said point of adjacency.

Alternatively, if desired, these two operations may be effected independently, as for instance, by connecting the wedge elements *o* to an operable shaft similar to *n* but independent thereof.

In the operation of the apparatus "the board" is placed upon the table *p* and brought beneath the deflector *h* against the uniformly rotating wheels *c d*. The rollers *e* ensure "the board" following the circumference of the wheel *c*, and the lower edge *h¹* of the deflector urges or diverts a portion of "the board" between the faces *c²* and *d³* of the wheels creating a channel shaped crease or depression, which is gradually squeezed or clinched laterally up to the point of adjacency of the wheels, at which point the desired U shaped crease is completely effected. During this operation, that part of "the board" associated with the 10 conical wheel rises to an obtuse angle relationship with the remainder of "the board" (see particularly Figure 3). This is found 15 advantageous for ensuring the requisite amount of cardboard being fed between the 20 rollers to constitute the U-shaped crease without any splitting or tearing of "the board". Figure 4 illustrates diagrammatically the deflector urging "the board" between the abrupt 25 faces of the wheels not far remote from their 30 point of adjacency and Figure 5 illustrates the three rollers ensuring "the board" being 35 bent to the circumference of one of the wheels or like elements, the deflector, in combination with the said rollers, bringing about the transverse, oblique or concave flexing of "the board".

In the present invention, therefore, "the board" is fed over two rotating wheels, or like elements, set on oblique intersecting axes, 40 and is urged between the divergent rims by means of a deflector, and bent to the circumference of one of the wheels by rollers, this 45 particular flexing of "the board" both longitudinally and laterally (with regard to the creasing) ensuring a very efficient crease.

The creasing in this invention is effected very expeditiously and generally efficiently, and "the board" may be easily folded to the desired angle formation without causing any 50 cracking, and retaining the full strength of "the board" at the bent portion.

If desired, the rollers *e* or their equivalent may be dispensed with, in which case the deflector *h* is designed so that it not only urges "the board" between the wheels in the creasing operation, but performs the additional function of bending "the board" circumferentially around the wheels, which function is normally performed by the rollers *e*. However, I find it advantageous to use the rollers to ensure the more efficient movement of "the board" through the apparatus during the creasing operation.

In the present invention "the board" is essentially adapted to be bent or flexed around

the peripheries of the wheels or like elements at or about their point of adjacency during the creasing operation, it being found that such bending or flexing is essential to the efficient creasing of "the board", and, further, provision is advantageously made whereby "the board" is caused to be bent transversely to an obtuse angular formation, as previously specified, to still further assist the effective operation of creasing.

I claim:

1. In an apparatus for creasing cardboard and the like, two peripherally curved rotary members placed at an angle relative to each other so as to be slightly spaced at their point of adjacency, means for rotating said members at uniform speed, and relatively stationary means located at fixed points with reference to the peripheries of said rotary members cooperating with said members so as to bend the cardboard, at the same time flexing the same along the curve of said members.

2. In an apparatus for creasing cardboard and the like, two peripherally curved rotary members having abrupt edges and placed at an angle relative to each other so as to be slightly spaced at their point of adjacency, means for positively rotating said members at a uniform speed, and adjustable relatively stationary means located at fixed points with reference to the peripheries of said rotary members cooperating with said members so as to bend the cardboard at the same time flexing the same along the curve of said members.

3. In an apparatus for creasing cardboard and the like, two peripherally curved rotary members placed at an angle relative to each other so as to be slightly spaced at their point of adjacency, means for positively rotating said members at a uniform speed, relatively stationary means located at fixed points with reference to the peripheries of said rotary members cooperating with said members so as to bend the cardboard at the same time flexing the same along the curve of said members, and a substantially flat table for feeding the cardboard to said members.

4. In an apparatus for creasing cardboard and the like, two peripherally curved rotary members placed at an angle relative to each other so as to be slightly spaced at their point of adjacency, means for positively rotating said members at a uniform speed, relatively stationary means located at fixed points with reference to the peripheries of said rotary members cooperating with said members so as to bend the cardboard, thereby causing it to be pinched between the cooperating faces of said members, at the same time flexing the board along the curve of said members, a substantially flat table for feeding the cardboard to said members, and means for adjusting the relative position of said members for enlarging or reducing the space.

5. In an apparatus for creasing cardboard and the like, two peripherally curved rotary members placed at an angle relative to each other so as to be slightly spaced at their point of adjacency, means for positively rotating said members, relatively stationary means located at fixed points with reference to the peripheries of said rotary members cooperating with said members so as to bend the cardboard transversely thereby causing it to be pinched between the cooperating faces of said members, and means causing the cardboard to follow for a short distance the contour of said members thereby flexing the cardboard.
- 10 6. In an apparatus for creasing cardboard and the like, two peripherally curved rotary members placed at an angle relative to each other so as to be slightly spaced at their point of adjacency, means for positively rotating said members, adjustable relatively stationary means cooperating with said members so as to bend the cardboard transversely, thereby causing it to be pinched between the cooperating faces of said members, and a plurality of rollers causing the cardboard to follow for a short distance the contour of said members thereby flexing the cardboard.
- 15 7. In an apparatus for creasing cardboard and the like, two peripherally curved members arranged to rotate upon intersecting axes so that at their point of adjacency said members will be slightly spaced apart, their inner faces at the operative point being parallel, means for positively rotating said members at a uniform speed, relatively stationary means cooperating with said members so as to bend the cardboard transversely, and a means for causing the cardboard to follow for a short distance the contour of said members thereby flexing the cardboard.
- 20 8. In an apparatus for creasing cardboard and the like, two peripherally curved members arranged to rotate upon intersecting axes so that at their point of adjacency said members will be slightly spaced apart, their inner faces at the operative point being parallel, means for positively rotating said members at a uniform speed, relatively stationary means cooperating with said members so as to bend the cardboard transversely, a means for causing the cardboard to follow for a short distance the contour of said members thereby flexing the cardboard, and means for adjusting said relatively stationary means.
- 25 9. Apparatus as specified in claim 7, including a driving shaft and in which one of said members is provided with a sleeve mounted on said driving shaft and the other member is rotatably mounted on a cylindrical boss mounted upon said sleeve and having its axis disposed obliquely to the axis of said shaft intersecting therewith, including a flexible driving member connecting said members, and means for displacing said boss upon said sleeve for adjusting the point of adjacency of said members.
- 30 10. Apparatus as specified in claim 7, including a driving shaft and in which one of said members is provided with a sleeve mounted on said driving shaft and the other member is rotatably mounted on a cylindrical boss mounted upon said sleeve and having its axis disposed obliquely to the axis of said shaft intersecting therewith, including a flexible driving member connecting said members, and means for displacing said boss upon said sleeve for adjusting the point of adjacency of said members.
- 35 11. Apparatus as specified in claim 7, including a driving shaft and in which one of said members is provided with a sleeve mounted on said driving shaft and the other member is rotatably mounted on a cylindrical boss mounted upon said sleeve and having its axis disposed obliquely to the axis of said shaft intersecting therewith, including a flexible driving member connecting said members, means for displacing said boss upon said sleeve for adjusting the point of adjacency of said members, and a compression spring interposed between said members.
- 40 12. Apparatus as specified in claim 7, including means for adjusting the relative position of said members, said means being adapted to simultaneously effect the adjustment of said relatively stationary means and said flexing means.
- 45 13. Apparatus as specified in claim 7, including means for adjusting the relative position of said members, said means being adapted to simultaneously effect the adjustment of said relatively stationary means and said flexing means, said adjusting means comprising two parallel shafts each incorporating left and right hand threads and being geared together, an arm associated with said members adapted to be operated by one of said shafts, and a slide carrying said relatively stationary means and said flexing means operated by said other shaft.
- 50 14. The method of creasing cardboard and the like, which consists in flexing the cardboard along a curved path, at the same time bending one edge only of the cardboard transversely to form an obtuse angle and creasing the board at the apex of the obtuse angle whereby a plurality of creases can be formed simultaneously.
- 55 In witness whereof I have hereunto set my hand.
- E. LESLIE BISHOP.
